US0D1020398S

(12) **United States Design Patent** (10) **Patent No.:** **US D1,020,398 S**
(45) **Date of Patent:** **** Apr. 2, 2024**

(54) **FOOD STORAGE CONTAINER**

(71) Applicant: **Shenzhen Fengshun Technology Co., Ltd.**, Shenzhen (CN)

(72) Inventor: **Zefeng Li**, Shenzhen (CN)

(73) Assignee: **Shenzhen Fengshun Technology Co., Ltd.**, Shenzhen (CN)

(**) Term: **15 Years**

(21) Appl. No.: **29/914,935**

(22) Filed: **Oct. 24, 2023**

(30) **Foreign Application Priority Data**

Sep. 13, 2023 (EM) 015033910-0001

(51) **LOC (14) Cl.** **09-07**
(52) **U.S. Cl.**

USPC **D7/629**
